UNITED STATES PATENT OFFICE.

BEN K. FORD, OF OAK PARK, ILLINOIS, ASSIGNOR TO UNION BED AND SPRING COMPANY, OF CHICAGO, ILLINOIS, A CORPORATION OF ILLINOIS.

BED-SPRING CONSTRUCTION.

Application filed November 4, 1922. Serial No. 598,991.

My invention pertains to structural novelties in bedsprings and relates more particularly to the means for mounting or supporting the bedspring on the bedstead and in the manner of attaching or anchoring the lower ends of the upright, spiral springs to the frame of the structure.

One purpose of the invention is the production of a bedspring appliance equipped with simple and effective positive-locking means for mounting it with facility and dispatch on bedsteads having different distances between their side-rails which constitute the supporting means for the bedspring proper.

This novel structural feature enables the improved bedspring to be employed on all usual bedsteads regardless of whether they are made of wood or metal and it compensates or cares for the differences in the transverse dimensions of such bedsteads.

Another aim or purpose of the invention is to provide a simple, inexpensive, and efficient fastening or means of attachment for the lower ends of the upstanding, spiral springs composing the major portion or cushion structure of the bedspring.

To the attainment of these and other desirable ends, I have devised the desirable and preferred embodiment of the invention illustrated in the accompanying drawing forming a part of this specification and throughout the several views of which the same reference characters have been used to designate like parts or elements.

In this drawing:—

Figure 1 is a fragmentary, horizontal section through a side portion of the bedspring above its frame structure;

Figure 2 is an enlarged, vertical cross-section through the side or marginal portion of the appliance;

Figure 3 is a fragmentary, sectional detail showing the manner of securing one of the bed-spring brackets on the frame; and

Figures 4, 5, 6 and 7 show the manner of mounting the spiral-springs.

Referring to this drawing, it will be perceived that the new and improved bedspring structure includes a suitable frame having a flat, edgewise-disposed, horizontal, longitudinal, side bar 10 to which a number of sheet-metal brackets 11 and the laterally bent ends 12 of a plurality of deformed, spring-supporting cross-bars 13 are riveted at intervals.

Each such bracket, which supports one of

the border spiral-springs, has a vertical wall 14, having an upright, narrow slot 15, and an inwardly-extended, horizontal, top wall 16, the section 14 having inturned stiffening and strengthening flanges 17, 17 along its two vertical margins, the part 16 having similar downwardly-extended flanges 18, 18 forming continuations of the parts 17, 17 but at right angles thereto.

The outer surface of each wall 14 bears against the inner face of the flat frame bar 10 and to assist in holding it firmly in position, such wall 14 has two spaced ears or lugs 19, 19 struck out of its plane the lower edges of which overlie the top edge of the frame side-bar 10.

The bent end 12 of the corresponding cross-bar 13 is accommodated between the flanges 17, 17 and bears against the inner face of the wall 14 of the bracket, the three parts 10, 14 and 12 being held firmly and fixedly together by a rivet 20 extended through registering or aligned holes in the three members.

Two or more of these spaced, slotted brackets accommodate in their elongated openings 15 a corresponding number (in the present instance three) of arms 21, laterally bent ears 22 at the outer ends of which are riveted to the depending flange of a horizontal angle-bar 23, the other outstanding flange of which is adapted to rest on the angle side-bar or similar side-rail 24 of the bedstead.

The inner end of each such element 21 has a bent terminal ear 25 notched in its lower end at 26 to fit over the top of the corresponding cross-bar 13, whereas the upper edge of each of such members 21 has a plurality or series of notches or recesses 27 any one of which, according to the adjustment, is designed and intended to receive that part of the wall 14 of the bracket directly above or forming the top margin of the slot 15.

Thus the supporting bar 23 may be adjustably positioned various distances from the frame bar 10 as may be required for different widths of bedsteads, whereby under all circumstances the element 23 may be brought to rest on the bedstead side-rail 24.

The weight of the bedspring is borne by the plurality of bars or arms 21 which are locked in position by the interfitting of those parts of the brackets above their slots engaging the corresponding notches or cavities,

downward swinging of the members 21 being limited and restricted by the bearing of the ears 25 on the cross-bars 23 of the bed-spring frame.

5 Obviously, therefore, the bed-spring by reason of these features of adjustability may be used on any bedsteads coming within such range or scope of adjustment.

10 Most of the coiled, cushion springs 28 of the structure are carried and supported directly by the transverse frame bars 13 as depicted in Figure 2, but the upright, border, spiral springs 29 are mounted individually directly on the several brackets or stand- 15 ards 11.

20 For the purpose of securing a simple and efficient anchorage or attachment of the lower coils of such marginal springs to their respective brackets, the top horizontal wall of each of the latter is supplied with an embossed, spring-centering, round boss 30, concentric with which on the under side of such top wall there is an embossed, arcuate rib 31 (Figures 6 and 7) providing on the top surface of such wall a correspondingly-shaped 25 channel or groove.

30 In line with this rib and its complementary groove there is a companion, curved, embossed rib 32 (Figures 4 and 7) on the top of such bracket wall forming on its under side a similar, arcuate groove, a round aperture being present at the registering, vertically-offset ends of such two ribs and grooves, from which point the ribs and 35 grooves taper longitudinally in opposite directions until they disappear or merge into the wall 16.

35 The lower coil of each border or side spring 29 has a tangential, outwardly-projecting end or terminal part 33, and the spring is applied to or mounted on its bracket by inserting such end 33 into the hole between the ends of the ribs and turning the spring in the proper direction to screw it 40 into place whereby a part of its lower coil and the end 33 are beneath the top wall of the bracket and the remainder of the spring above it, a portion of the spring occupying the two registering curved grooves referred to.

45 While thus screwing the spring into place, the straight end 33 yields or flexes sufficiently to permit this operation, but when the spring has been fully screwed home and anchored in place, the part 33 rests flat against one of the flanges 18 or against the wall 14 locking the spring in place and effectively preventing its unintentional loosening or removal.

50 If circumstances require, however, any one of such springs may be unscrewed and de-mounted from its supporting bracket.

55 Only one preferred embodiment of the invention has been illustrated and described, but it is to be borne in mind that the invention is susceptible of a number of satisfactory

embodiments and that many mechanical changes may be incorporated in the bed-spring presented without departure from the substance and essence of the invention and without the sacrifice of any of its material and substantial structural and functional 70 benefits and advantages.

I claim:

1. In a bed-spring structure of the character described, the combination of a main-frame having a plurality of vertically-disposed slots and also having a plurality of cross-bars, a number of adjustable arms each slidingly accommodated in one of said slots, and a supporting-bar connecting the outer 80 ends of said arms and designed to support the bed-spring frame by resting on a bedstead side-rail, the tops of said arms having a series of notches to receive those parts of the frame at the tops of said slots, whereby 85 to hold the arms and supporting-bar in adjusted position, each of said arms at its inner end being bent laterally to provide means to bear on the corresponding cross-bar of the frame.

2. In a bed-spring construction of the character described, the combination of a bed-spring frame having a plurality of vertical slots, a number of adjustable arms each slidingly accommodated in one of said slots, 95 and a supporting-bar connecting the outer ends of said arms and designed to support the bed-spring frame by resting on a bedstead side-rail, the tops of said arms having a series of notches to receive those parts of the frame at the tops of said slots, whereby 100 to hold the arms and supporting-bar in adjusted position, the inner end of each arm bearing on the frame.

3. In a bed-spring structure of the character described, the combination of a bed-spring frame having a side-bar, a plurality of upright vertically-slotted sheet-metal brackets bearing in spaced relation against the inner face of said side-bar, a plurality of frame cross-bars each having a bent end bearing against the inner face of one of said brackets, means fastening said bracket and cross-bar bent end to said frame side-bar, each bracket having a pair of lugs integral therewith and struck up out of the metal thereof overlying the top of said frame side-bar, outstanding arms having on their tops a series of notches accommodated slidingly in said bracket slots, means on said arms adapted to rest on a bedstead side-rail, each arm having a bent end overlying and adapted to bear on the top of the corresponding frame cross-bar, said arm notches being adapted to receive those portions of the brackets at the tops of their slots and to hold the arms in adjusted position, each bracket having a laterally-bent horizontal top wall having an aperture therethrough and tapering registering arcuate grooves in 130

- its upper and lower faces leading to said aperture, and an upright spiral-spring mounted on said bracket and having a convolution accommodated in said arcuate 5 groove and aperture and a straight terminal portion at its lower end bearing against a portion of said bracket to prevent unintentional unscrewing and removal of the spring.
- 10 4. In a bed-spring structure of the character described, the combination of a bed-spring frame, a slotted bracket mounted thereon, an outstanding frame-supporting bar slidingly adjustable in said slot, and an upright spiral-spring mounted on said bracket. 15
5. In a bed-spring structure of the character described, the combination of a bed-spring frame having a side-bar, a slotted sheet-metal bracket secured to said side-bar 20 and having lugs struck out of its body overlying and bearing on the top of said side-bar, an outstanding frame-supporting bar slidingly adjustable in said slot, and an upright spiral-spring mounted on said bracket. 25

In witness whereof I have hereunto set my hand.

BEN K. FORD.
